CASKET

Wayne H. Williams, Bristol, Va.

Application March 3, 1943, Serial No. 477,869

2 Claims. (Cl. 27—4)

This invention relates to a casket that is used for burial purposes, and has particular application to such a casket when displayed, before, during and after the burial ceremonies.

An object of the invention is to provide a casket which when the head section or head cap is in open position, provides ample room for insertion of the corpse within the casket, and without disturbing the delicate interior furnishings or decorations of the casket.

Another object of the invention is to provide a two-piece casket head cap which when in open or closed position presents no catches or clasps which often tear the veils which are used on the casket after a body has been placed therein, and during the burial ceremonies. These veils are very expensive, some of which cost as much as one hundred dollars. They are used over and over again and have been subject to damage by the catches which heretofore were used to hold the head cap in closed position on the casket.

Another object of the invention is to provide a casket having a head cap consisting of two hinged covers, each hinged to the opposite sides of the O. G., or side walls of the casket.

A further object of the invention is to provide a half couch type of casket having folding sections for the head cap of the casket, including one section hinged to the back O. G., and the other section composed of two parts, hinged to each other, one part of said two part sections being hinged to the front O. G.

Still another object of the invention is to improve the general appearance and attractiveness of the casket, both in open and in closed position.

Another object of the invention is to provide a concealed catch on the vertical wall of the foot cap, for holding the front and back head cap sections in closed position, as well as other concealed catches on said parts for the same purpose.

Other objects and advantages will appear hereinafter, throughout the specification.

In the drawings:

Figure 1 is a perspective view of the preferred form of the invention, showing the head cap sections in open position;

Figure 2 is a view similar to Figure 1, but showing the head cap sections in closed position;

Figure 3 is a top plan view of the casket shown in Figure 2; and

Figures 4, 5 and 6 disclose different scroll cuts for the back head cap.

Illustrated in Figures 1, 2 and 3 is an octagon sided casket 1, which, however, may be con-

structed with four, six or eight sides according to the type of casket desired. The casket has the usual foot cap 2, a back O. G. 3, and a front O. G. 4. That portion of the back O. G. 3, which is adjacent to the head sections is numbered 5.

The foot cap has a vertical wall 6 and below this vertical wall is a cross piece 7 forming a support for the lower sides of the sectional head cap.

10 The head cap consists of a back section 8 which is hinged at its rear extremities to the upper or head portion of the back O. G. 5, and a two-part front section 9. The lower part 10 is in reality the head portion of the front O. G., and 15 is hinged at 12 and 13 to the lower front side of the casket. This part 10 is hinged at 14 and 15 to the upper part of the front head section 11, as shown in Figure 2 of the drawings.

The back section head cap 8 has a forward oval 20 convex edge 16 and a right hand straight edge 17 which makes a right angle with the rear side of the coffin, and an angularly related left hand straight edge 18 which meets a similar edge 19 of the top piece 20 when the parts are in the 25 position shown in Figures 2 and 3. The top piece is provided with hinges 21 and 22 by which it is pivoted to the top O. G. 23.

The upper part of front head section 11 has an oval concave edge 24 which forms a smooth 30 almost unbroken surface with the convex edge 16 of the back section head cap. The parts are connected together by the concealed eye 25 on the back section head cap and hook 26 on the upper part of the front head section 11, which latter is provided with a right hand straight edge 27 having a concealed socket (not shown), which receives the spring-pressed stud member 28 on vertical wall 6 when the parts are in closed position.

40 Similarly, the top piece 20 is provided with a spring-pressed stud member 29 which is received in the socket 30 of the left hand side edge 31 of section 11. The numerals 32 and 33 indicate the usual supporting or carrying handles for the casket.

The section 11 is provided with rosettes 34 which are attached by cords 35 to the section 11 to assist in opening the front head section 9.

The interior of the back section head cap 8 50 may be provided with a roll cap 36, a ray 37 and a centrally located corsage 38 to enhance the appearance of the interior when exposed to view.

Figures 4, 5 and 6 disclose several different types of scrolls forming the forward edges of the back section head cap, it being understood of course

that the edge of the front head section (not shown) will be constructed so as to mate with the several forms illustrated in these figures. The several members 5, 11, 20 and the interior of the coffin, are suitably padded with material indicated at 39.

It will be noted that several advantages are obtained by the above construction. Among these are the concealed hardware comprising the catches 25, 26, 29 and 29 and 30 which provide no sharp edges for the veil to be caught upon and torn. These catches are entirely concealed when the parts are in the position shown in Figures 2 and 3. The back section 8 and the two-part front section 9 provide a larger opening for insertion of the body. Additionally when the parts are in the position shown in Figure 2, the coffin may be placed on a higher pedestal during the burial ceremonies and still permit a view of the entire head of the deceased. The top piece when opened forms a support for pillows and other accessories for supporting the head of the deceased in fully exposed position.

Having thus described my invention, what I claim is:

1. A casket having a closed top for the lower end portion thereof and an upper end portion capable of being opened, said upper end portion being lined and comprising; side walls, a back head cap section, means pivoting said back section to a side wall to support said back head cap section in an upstanding position to display the lining on the interior thereof, and having a forward curved edge, a front section head cap, means pivoting the front section to another side wall of said casket to permit the same to be pivoted to an open position substantially parallel with the casket wall to display the lining on the interior of

said front section and to obscure a portion of the side wall of the casket, said front section head cap having a rear curved edge, the curved edges of the head sections when in closed position being in abutting relation to each other and preventing transverse movement of said head cap sections with relation to each other, said closed top having supporting means and said head cap sections having side edges adapted to rest upon said supporting means when the head cap sections are in closed position.

2. A casket having a closed top for the lower end portion thereof and an upper end portion capable of being opened, said upper end portion being lined and comprising side walls, a back head cap section, means pivoting said back section to a side wall to support said back head cap section in an upstanding position to display the lining on the interior thereof, and having a forward curved edge, a front section head cap comprising two pieces pivoted together, means pivoting the front section to another side wall of said casket to permit the same to be pivoted to an open position substantially parallel with the casket wall and to display the lining on the interior of said front section and to obscure a portion of the side wall of the casket, said front section head cap having a rear curved edge, the curved edges of the head sections when in closed position being in abutting relation to each other and preventing transverse movement of said head cap sections with relation to each other, said closed top having supporting means and said head cap sections having side edges adapted to rest upon said supporting means when the head cap sections are in closed position.

WAYNE H. WILLIAMS.
